UNITED STATES PATENT OFFICE.

JOSEPH GEBHART, OF ZION CITY, ILLINOIS.

CORK-EXTRACTOR.

1,084,422.

Specification of Letters Patent. Patented Jan. 13, 1914.

Application filed May 17, 1913. Serial No. 768,324.

To all whom it may concern:

Be it known that I, JOSEPH GEBHART, a citizen of the United States, residing at Zion City, in the county of Lake and State 5 of Illinois, have invented new and useful Improvements in Cork-Extractors, of which the following is a specification.

The present invention relates to an attachment for bottles and corks therefor, the 10 object of the same being to provide a device whereby the cork may be easily and quickly removed from the bottle when desired.

With the above recited object in view, and others which will appear as the nature of 15 the invention is more fully understood, the improvement resides in the construction, combination and arrangement of parts set forth in the following specification and falling within the scope of the appended claim.

20 In the drawing:—Figure 1 is a perspective view illustrating a cork and bottle provided with my improvement and showing the means for extracting the cork from the bottle neck, Fig. 2 is a vertical longitudinal 25 sectional view through the cork and bottle neck, and illustrating the position of the fulcrum bar when the cork is not to be extracted from the bottle, Fig. 3 is a perspective view of the extractor, Fig. 4 is a detail sectional 30 view through the cork showing the same provided with a central post in the form of a cotter pin.

Referring now to the drawing, the numeral 1 designates an ordinary bottle neck 35 which is provided, adjacent its mouth, with the usual depression 2, and disposed within this depression is a wire ring 3. This ring is formed with an outturned lip 4 in which is pivotally connected a fulcrum rod 5. 40 The free end of the fulcrum rod is provided with a substantially V-shaped depression, the purpose of which will presently be described. The cork is indicated by the numeral 6, and is of the ordinary construction. 45 The cork has passing centrally therethrough a rod 7, each of the opposite ends of which being provided with heads 8 and 9 respectively which bear against the inner and

outer faces of the said cork. The rod extends beyond its outer head and is bent to 50 provide an eye 9.

When the cork is to be extracted from the bottle, the fulcrum lever is swung upwardly to the angle illustrated Fig. 1, and the extracting member, designated by the numeral 55 11, which is constructed of a single piece of wire and which has one of its ends formed with a lip 12, is rested upon the V-shaped end of the fulcrum rod and its lip inserted within the eye. A downward pressure upon 60 the portion of the extractor extending beyond the fulcrum rod will cause the removal of the stopper from the bottle. The member 11 at the juncture of its angular portions is substantially V-shaped in cross section, as 65 clearly shown in Figs. 1 and 3 of the drawings, whereby the said V-shaped portion will find an effective bearing within the V-shaped end of the fulcrum rod.

In Fig. 4 of the drawings, I have illustrated the cork 6' provided with a rod, in the nature of a cotter pin 7', the eye 9' of which being arranged above the top of the cork and the arms of which passing through the cork and extending below the bottom 75 face thereof will bend in opposite directions to sustain the said cotter pin securely upon the cork to prevent the said cotter pin being forced outwardly when the fulcrum member is applied to the eye thereof, and the said 80 eye also prevents the member 7' being passed downwardly through the cork.

From the above description, taken in connection with the accompanying drawing, the simplicity of the device, as well as the advantages thereof will, it is thought, be perfectly apparent to those skilled in the art to which such inventions appertain without further detailed description. 85

Having thus described the invention, what 90 I claim is:—

The combination with a bottle having its neck formed with an annular depression, and a cork for the bottle having its outer face provided with an eye, of a wire ring 100 arranged within the depression of the bottle

neck and having an outturned lip, a rod having one of its ends pivotally secured to the lip of the ring to permit of the swinging of the rod upon the bottle neck, said rod 5 having its free end formed with a V-shaped depression, an extractor member adapted to be fulcrumed within the depression of the rod and to have one of its ends provided

with a lip which is adapted to be inserted within the eye provided upon the cork. 10

In testimony whereof I affix my signature in presence of two witnesses.

JOSEPH GEBHART.
